TIE-PLATE

James K. Boyd, Wilkinsburg, and Frank F. Slick,
North Braddock, Pa.

Application May 29, 1933, Serial No. 673,513

9 Claims. (Cl. 238—304)

This invention relates to rail tie-plate assemblies, one of the objects being to safely secure railroad rails. Another object is to secure them so they may be easily shifted when their heads become worn. Other objects may be inferred.

5 A specific example of the invention is illustrated by the accompanying drawings, the various figures being as follows:

Figures 1 and 2 are side views of the tie-plate assembly, showing the shifting of the rail.

10 Figure 3 is a cross-section from the line III—III of Figure 2.

Figures 4 and 5 are top plans of details from the first two figures.

15 Figures 6 and 7 are cross-sections from the lines VI—VI and VII—VII of Figures 4 and 5, respectively.

Figure 8 is a side view of a modification.

Figure 9 is a cross-section from the line IX—IX of Figure 8.

20 Figure 10 is a detail from Figures 8 and 9.

A bar 1 is upwardly looped to provide lugs 2 adjacent the base of a rail when the bar is placed thereunder.

25 The bar is positioned by a rail base-plate 3 having a groove 4 in its bottom receiving the bar and apertured at points registering with the lugs provided thereby. It has a thick central portion 5 whose top surface is inclined at the proper angle to give the rail its desired cant. This portion incidentally acts as a reinforcement above the groove.

30 In the drawings, the bar 1 is looped at points calculated to enable the resulting lugs 2 to ad-35 jacently straddle the base of the rail to be secured. Clips 6, 6^a have end portions 7 adapted to engage the base of the rail, and are respectively apertured at different distances from these portions for application to the lugs 2. Thus, they are adapted to hold the rail at different positions when interchanged on the lugs.

35 Referring to the side elevation, the left-hand clip 6 is apertured nearer to its end portion 7 than is the right-hand clip 6^a. This holds the rail with its center line offset to the left from the middle point between the lugs 2. It is to be understood that these lugs are spaced sufficiently to permit some movement of the rail therebetween.

40 This rail is assumed to be the highest of a curved track section, the right-hand side of its head being therefore subjected to rather rapid flange-wear. When this becomes excessive, the clips are interchanged so the rail is moved to the right, this being illustrated by dotted lines.

In one instance, each clip 6, 6^a is held by a wedge-seat 8 constructed to engage it when inserted in the lug to which it is applied. This wedge-seat has a downward projection 9 which registers with the aperture in the clip. An arcuate wedge 10 engages the top of the wedge-seat 8 and the under side of the lug.

45 The wedge-seat and the lug are respectively constructed to provide arcuate surfaces for receiving the wedge. The upper surface of the 10 wedge itself is laterally curved to fit the lug.

The wedge is sufficiently long so its small end projects beyond the surface of the lug and wedge-seat, and it is made of malleable metal so this end may be displaced to lock it against removal.

15 An alternate means for holding a clip on its lug includes a spring piece 11 having a central downwardly looped portion which projects into the aperture of the clip when the piece is placed in the lug.

20 A headed bolt 12 is then inserted through the lug, an unthreaded member 13, having flat sides arranged different distances from the axis of the bolt, being first applied thereto. A threaded member 14, similarly constructed to the member 13, is adapted for screw-threaded engagement 25 with the bolt 12. Similar sides of the two members are faced towards the spring piece 11, and the head of the bolt 12 turned to effect engagement. Thus, the clip may be held down with 30 varying forces which depend upon which of the sides of the two members are faced towards the spring piece 11, the latter preventing looseness.

35 The bolt is sufficiently long to enable rotation 35 of the member 14 for a few turns before engagement of the spring piece 11 is effected, as it would be troublesome to start the bolt into this member if otherwise.

40 Although a specific example of this invention is disclosed in accordance with the patent stat-utes, it is evident that various subcombinations of the whole might be used with other constructions; therefore, the invention is not to be lim-ited exactly thereto except as defined in the fol-45 lowing claims.

We claim:

1. A tie-plate assembly including a bar which is upwardly looped at at least one point to provide a lug adjacent the base of a rail when the bar is placed thereunder, and a rail base-plate having a groove in its bottom receiving said bar and which is of a depth at least equal to the thickness of the latter, said groove being apertured at a point registering with the lug provided thereby,

- said base-plate being thereby adapted to carry the rail and position said bar.
2. A tie-plate assembly including a lug, a clip apertured for application to said lug, an arcuate wedge and a wedge-seat constructed to engage said clip, said wedge-seat and said lug being constructed to provide opposed surfaces for receiving said wedge.
3. A tie-plate assembly including a lug, a clip 10 apertured for application to said lug, an arcuate wedge and a wedge-seat constructed to engage said clip, said wedge-seat and said lug being respectively constructed to provide arcuate surfaces for receiving said wedge therebetween, and 15 said wedge being constructed of malleable metal and of sufficient length for its small end to project beyond the surfaces of said lug and wedge whereby its end may be displaced for locking purposes.
- 20 4. A tie-plate assembly including a lug, a clip apertured for application to said lug, an arcuate wedge and a wedge-seat constructed for application to said clip and having a downward projection registering with the aperture therein, said 25 wedge-seat and said lug being respectively constructed to provide arcuate surfaces for receiving said wedge therebetween, and said wedge being constructed with its upper arcuate surface curved to fit the lug and, further, being of malleable 30 metal and of sufficient length for its small end to project beyond the surfaces of the lug and wedge-seat whereby it may be displaced for locking purposes.
- 35 5. A tie-plate assembly including a bar which is upwardly looped at one or more points to provide a lug or lugs adjacent the base of a rail when the bar is placed thereunder, and a rail base-plate having a central thick portion, a groove in its bottom, this for receiving said bar, and apertures at 40 points registering with said lugs provided by said bar when in said groove, the latter being of a depth at least equal to the thickness of said bar.
- 45 6. A tie-plate assembly including a bar which is upwardly looped at spaced points to provide a pair of upstanding lugs that can straddle the base of a rail, a rail base-plate having a groove in its bottom receiving said bar and which is of a depth at least equal to the thickness of the latter, said groove being apertured at points regis- 50 tering with the lugs provided thereby, said base-plate being thereby adapted to position said bar and carry a rail, clips having end portions for engaging the base of a rail and being respectively apertured at different points from these ends for

application to the lugs provided by said bar, said clips being thereby adapted to hold the rail at different positions when interchanged on said lugs, and means for holding said clips on said lugs.

5 7. A tie-plate assembly including a bar that is upwardly looped at at least one point to provide a lug adjacent the base of a rail when the bar is placed thereunder and a rail base plate having a groove in its bottom receiving said bar and a thickened portion that is in line with said groove, the latter being of a depth at least equal to the thickness of said bar, said plate being apertured at a point registering with said lug so that the latter may project upwardly therethrough.

10 8. A tie-plate assembly including a bar that is upwardly looped at at least one point to provide a lug adjacent the base of a rail when the bar is placed thereunder, a rail base plate having a groove in its bottom receiving said bar and a thickened portion that is in line with said groove, the latter being of a depth at least equal to the thickness of said bar, said plate being apertured at a point registering with said lug so that the latter may project upwardly therethrough, a clip 15 that is apertured for application over said lug, a wedge-seat constructed for passage through said lug transversely above said clip and a wedge member constructed for passage through said lug and adapted to bear on said wedge-seat.

20 9. A tie-plate assembly including a lug, a clip apertured for application to said lug, a spring piece constructed for passage through said lug above said clip, a headed bolt for insertion 25 through said lug above said clip and said piece, an unthreaded member having flat sides arranged different distances from its center and adapted to receive said bolt, and a threaded member similarly constructed to said first named member and 30 adapted for screw-threaded engagement with said bolt, the first and second named members being 35 adapted to hold down said clip with varying forces by contact of their various sides there- 40 with and said piece being adapted to frictionally hold said members in place, said bolt being suffi- 45 ciently long so that when passed through said unthreaded member and through said lug its end may be threaded into engagement with said threaded member while both of said members are 50 mutually separated sufficiently to be free from the full pressure of said spring piece there-against.
